UNITED STATES PATENT OFFICE

HAROLD HUTCHINSON, OF LONDON, ENGLAND, ASSIGNOR TO G. K. SYNDICATE LIMITED,
OF LONDON, ENGLAND, A BRITISH ORGANIZATION

FIRE EXTINGUISHING DEVICE

Application filed January 29, 1931, Serial No. 512,171, and in Great Britain February 18, 1930.

The present invention relates to fire extinguishing pistols from which a fire extinguishing composition is ejected due to the explosion of a propellant explosive and has 5 for its object the provision of such a pistol which has the minimum of working parts, is easy to cock, not liable to be put out of action, and having its extinguishing composition efficiently sealed against deterioration should 10 the said composition have to remain in the pistol for a long time before use.

Fire extinguishing pistols have hitherto been constructed in which a striker mounted coaxially with the cartridge is movable 15 manually to cocked position independently of the trigger a pivoted catch being provided to restrain the striker from movement in either of two positions, the said catch being adapted to be rocked about its pivot to release 20 the striker for operative movement when the trigger is pressed.

In such pistols the spindle on the end of which the striker is carried has been provided with a handle by which the striker can 25 be pulled back against the action of a spring surrounding the spindle till the pivoted catch operates to hold the striker in cocked position. In this arrangement however as it is necessary to provide a strong spring to move 30 the striker from cocking position to the detonating cap, a great force is required to cock the pistol thus women have great difficulty in using the pistol. Moreover, the handle of the striker extending from the rear of the 35 device has the disadvantage that in the event of a sharp blow as by way of a fall, the catch device fails to hold the striker and the charge is caused to be exploded, and frequently the mechanism is broken. Further- 40 more the catch and trigger operation of the striker as above described necessitates a large number of separately formed parts being employed in the detonating mechanism.

With a view to overcoming the above mentioned drawbacks according to the present invention the striker is carried on one arm of a two armed lever which is restrained to bring the striker on to the detonator cap or the like for detonating the propellant explosive by a spring, the end of the other arm 45

of the lever engaging a pivoted trigger, when the lever is pulled back to cock the pistol, the lever then clearing the trigger which is thus permitted to move under the action of a spring or like constraint so that when the 55 lever is released its return movement is obstructed by the trigger and can be prevented by the engagement of part of the trigger with a fixed part or projection in the pistol casing. When the trigger is pressed and moved 60 sufficiently against the action of the spring or like part constraining it, then the lever is released and the striker is brought into detonating contact with the detonator cap and the pistol is thus fired. The part of the trig- 65 ger engaging the lever is preferably arcuate about the trigger pivot so that there is no movement of the lever upon movement of the trigger until the trigger clears the lever. This enables a trigger to be used without 70 connecting links for release and is believed to be a novel simplification of trigger release mechanism.

Preferably the trigger spring is a weak one so that the trigger readily yields to pressure, and the lever spring must be a strong one, to produce the necessary momentum of the striker required to detonate the cartridge cap. Also a weak cushioning spring may be provided to keep the striker normally just 80 clear of the cap.

The accompanying drawing shows the preferred embodiment of the invention.

In the said drawing, Figure 1 is a sectional elevation of the improved pistol showing 85 the trigger cocked, and Figure 2 is a view similar to Figure 1 but with the trigger "uncocked" or released.

Figure 3 is an end view of the pistol.

As shown, the mechanism is mounted in 90 the usual pistol handle casing 1, which may be provided with a renewable cartridge 2.

It will be seen that the preferred mechanism comprises a two armed lever 3 of flattened V-shape pivoted at 4 in the casing 1 95 immediately below the back end of the cartridge 2. One arm 3a of the lever is about three times as long as the other arm 3b, and on the longer arm 3a, at about two thirds its distance from the pivot 4, is formed or other- 100

wise applied the striker 5, while the shorter arm 3b is adapted to engage the trigger 6 as will be hereinafter more particularly described.

5 The main spring 7 for moving the striker to the cap 2a is secured to the shorter arm 3b of the lever near its tip and at a point 8 in the downward extension 1a of the casing 1, and is strong enough to impart the required 10 momentum to the striker to enable the cap 2a to be discharged when the lever is released as hereinafter described. A cushioning spring 9 is mounted on the lever pivot 4 (as shown) so that when the trigger 3 has 15 been released the striker 5 is normally held clear of the location of the detonator cap 2a of the cartridge 2.

The tip of the arm 3a of lever 3, projects 20 out of the casing 1 as shown at 3c, and is fashioned as a finger piece to provide a convenient cocking means. To permit the projection of the tip 3c the casing 1 is formed 25 with an arcuate slot 10 in which the tip moves, the said slot being normally closed by an arcuate guard or dust cover 11 secured 30 and carried on the tip just within the casing 2 at 12, so as to be able to rock on the tip as the lever 3 moves, such guard being sprung to conform to the radius of the casing.

30 The trigger 6 is pivoted in the casing at 13, under the action of a weak spring 14 mounted about the trigger pivot, one end of which spring engages the casing while the other end 14b is hooked on the trigger normally to 35 hold same in the position shown clearly in Figure 2. The trigger 6 is formed with a part 6a adapted to be pressed by the finger of the operator in well known manner, and has an upwardly directed extension 6b which is 40 formed with an arcuate face 6c which engages the end 3b of the lever 3 when the mechanism is cocked, and a downward extension 6d which engages on a part of the casing 1 surrounding the trigger to limit the 45 possible outward turning movement of the trigger.

The operation of the mechanism will be readily understood.

To cock the pistol the part 3a of the lever 50 3 is retracted, by pressing the finger piece 3c, whereupon the end of the arm 3b of the lever passes over the face 6c of the trigger till it just clears the trigger, the trigger 6 moving slightly in a clockwise direction to allow the 55 lever 3 to be thus moved. The return spring 7 for the lever 3 is then extended and acts on the lever 3 which in turn re-engages on the trigger 6 at surface 6c tending to move the trigger in an anti-clockwise direction. The 60 anti-clockwise movement of the trigger is however limited by the engagement of the abutment 6d of the trigger on the casing 1, and consequently the pistol is held cocked. Upon pressing the trigger 6, after cocking, in 65 the usual way with the finger at 6a the trigger

moves in a clockwise direction till its end 6c just clears the trigger 6 allowing the same to move under the action of its return spring 7 to cause the striker to strike the detonator cap 2a of cartridge 2 which is thereby exploded. 70 The striker 5 is subsequently held clear of the location of the cap 2a by means of the weak spring 9 acting on the lever 3.

It will be seen from the arrangement described, that owing to the distance of the tip 75 3c of the lever 3 from the pivot 4, being so great compared with the distance of the point of action of the main spring 7 on the lever from the pivot, only a small force will have to be exerted to cock the pistol. Further the 80 movement of the trigger 6 is accomplished without great effort after cocking. The pistol can thus be readily used by a woman or by people whose strength is below normal.

The mechanism above described is preferably mounted in a fire extinguisher pistol handle of the usual form, which may, as already mentioned, be provided with a renewable cartridge though I prefer not simply to flare and cap the discharge end 2b of the cartridge as is usual but to provide the end with a grooved or expanded part (as shown at 2c in the drawing) close to the discharge end into which portion is first inserted a waterproofed disc, which is then covered with a liquid or semi-plastic waterproof composition and allowed to set after which a second disc is pressed into the expanded or grooved part, the discs as well as the waterproof composition preferably entirely filling up the enlarged or grooved area, the latter disc being covered with a thin sheet of metal foil, and finally treated with a waterproof dope or enamel.

This sealing arrangement is preferred because the cap seal above described having no restraining obstruction has been found in practice under certain conditions to work loose. The improved seal is positive and more efficient in action.

110 It will be seen that the firing mechanism provided according to my invention comprises only two members pivoted in the pistol casing as against ten or eleven members usually required in the mechanism previously employed, and for this reason an arrangement according to the invention is simpler and cheaper to manufacture than is the known mechanism.

115 It is to be clearly understood that my invention can be embodied in arrangements, other than the preferred embodiment above described and I wish it to be understood that this particular description is not to be interpreted restrictively.

120 Having thus described my invention, what I desire to secure by Letters Patent of the United States is:—

1. Fire extinguishing pistol with striker mechanism disposed in a casing and opera- 130

5 tive to strike a detonator cap to propel a fire extinguishing composition, the said mechanism comprising a two-armed lever pivoted in the casing, the tip of one arm projecting through the casing, a weak spring fitted to said pivot to normally hold the lever in a predetermined position, and a spiral main spring operating on the lower arm of the two-armed lever with a substantially straight pull when the lever is cocked.

10 2. Fire extinguishing pistol with striking mechanism disposed in a casing and operative to strike a detonator cap to propel a fire extinguishing composition, the said mechanism including a two-armed pivoted lever, a striker on one arm, a main spring normally pulling the other arm, and a weak spring arranged to hold the striker arm with the striker just clear of the detonator cap, when the two-armed lever is in the uncocked position with the main spring only slightly loaded.

15 3. Fire extinguishing pistol with striking mechanism disposed in a casing at the butt end of a barrel adapted to receive a detonating device to propel a fire-extinguishing composition, the said mechanism including a two-armed pivoted lever, a striker on one arm which extends through a slot in said casing, a main spring normally pulling the other arm, a weak spring arranged to hold the striker arm with the striker just clear of the detonator cap, when the two-armed lever is in the uncocked position with the main spring only slightly loaded, and a cover slidable in the said casing and carried by the striker arm to cover the aforesaid casing slot.

20 In testimony whereof I have affixed my signature.

25 HAROLD HUTCHINSON.
